(57) **CLAIM**

The ornamental design for a display screen with user interface, as shown and described.

DESCRIPTION

FIG. 1 is a front view of a display screen with user interface showing the new design;

FIG. 2 is a front view of a display screen with user interface showing an alternative embodiment thereof;

FIG. 3 is a front view of a display screen with user interface showing an alternative embodiment thereof; and,

FIG. 4 is a front view of a display screen with user interface showing an alternative embodiment thereof.

The broken line showings of the remainder of the user interface and of the tablet computer illustrate unclaimed environment and form no part of the claimed design.
